METHOD OF MAKING DOILIES

Ferdinand W. Mostertz, Philadelphia, Pa.

Application March 16, 1936, Serial No. 69,110

1 Claim. (Cl. 28—1)

This invention relates to a doily or mat cut from woven material and has special reference to the cementing of the back thereof to prevent displacement of the threads at the points of severance, and also to act as a non-skidding means when the doily is used on smooth polished surfaces.

An object of the invention is to provide a doily or protective pad or mat of any configuration cut from a width of woven material and in which the severed threads are held to prevent disarrangement.

Another object of the invention is to provide a doily or mat cut from fabric having pile designs and in which the severed ends of the pile threads are also held to prevent displacement.

A still further object of the invention is to provide a rubber backed doily or protective mat which will be liquid proof and will also prevent slippage when used on smooth polished surfaces.

According to the invention, the doily or protective mat is cut from a loom width of woven material having thereon a self-contained pile decoration, and a cementitious backing for connecting the severed threads of the woven and pile fabrics to prevent disarrangement at points of severance.

The drawing illustrates an embodiment of the invention and the views therein are as follows:

Fig. 1 is a plan view of woven pile fabric showing the manner in which the doilies with their self-contained patterns are cut therefrom,

Fig. 2 is a top plan view of a finished doily with its self-contained design, and

Fig. 3 is a fragmentary longitudinal section, taken on line 3—3 of Fig. 2.

In the manufacture of the present invention, a width of material 6, as shown fragmentarily in Fig. 1, is provided, said width of material comprising a backing 7 formed of ordinary weaving and self-contained motifs or patterns 8 formed by pile loops 9, either cut or in the form of frise or frizette to provide a variation in the surface textures of the doilies.

The pile loops 9 forming the motifs in the backing 7 may be made in accordance with my United States Letters Patent No. 1,934,942, dated November 14, 1933, and No. 1,914,278, dated June 13, 1933.

The motifs or patterns 8 contained in the finished individual doilies or mats and which may

be of any configuration desired, are obtained by use of the well known jacquard mechanism operating in conjunction with the ordinary weaving mechanism used for forming the backing 7.

When the width of material 6 with its self-contained patterns or motifs has been completed, the under surface thereof is treated with a cementitious compound 11. This cementitious compound firmly binds together the threads of the woven and pile fabrics, so that when the individual doilies are cut from the width material, the threads at the cut or serrated edges will be cemented together and held against disarrangement.

The cementitious backing, which may be of any desired material such, for instance, as a rubber compound, in addition to forming a binding connection between the threads, particularly at the points of severance, acts also to prevent slipping of the mats when used on smooth polished surfaces, and prevents liquids from seeping through onto said surfaces, and further provides the doily with a flexible but firm backing which at all times retains its shape without creasing or distorting of the doily in any way.

After the width of material has been treated with the cementitious compound, the mats or doilies each containing a completed motif, design or decoration, are cut or stamped from the said material, thus producing a neat individually modified doily, as shown in Fig. 2, in which the severed threads of the edges are firmly held against disarrangement or fraying by the cementitious compound.

While the doily has been illustrated as circular, it may be of any shape desired.

Of course the doily illustrated may be modified and changed in various ways without departing from the invention herein set forth and hereafter claimed.

The invention is hereby claimed as follows:

The method of producing unbound doilies comprising the steps of first weaving frise fabric in loom widths with individual motifs thereon formed transversely of the fabric and mainly by the pile threads, then coating the entire back of the piece with a material which will bind all threads of the fabric, and then cutting the individual doilies from the width of fabric, whereby all threads are held against fraying.

FERDINAND W. MOSTERTZ.
